UNITED STATES PATENT OFFICE.

EDWARD S. CORNELL, JR., OF WATERTOWN, CONNECTICUT, ASSIGNOR TO CHASE COMPANIES, INC., OF WATERBURY, CONNECTICUT, A CORPORATION.

TRAFFIC MARKER FOR PAVEMENTS.

Application filed February 23, 1928. Serial No. 256,217.

This invention relates to an improvement in traffic markers for pavements and has for its object the production, at a low cost for manufacture, of a simple and highly-visible marker constructed with particular reference to capacity for resisting displacement.

With this object in view, my invention consists in a concavo-convex sheet-metal traffic marker characterized by being struck downward to form a recess in its convex upper face and a supporting shoulder projecting from its concave under face; an axial passage extending through the down-struck portion of the plate; and an anchoring-member comprising a shank passing through the said axial passage into the pavement and an overhanging head adapted to fit into the said recess; whereby the rim of the plate may be embedded itself in the pavement to prevent lateral displacement of the plate and to prevent its being accidentally pried loose by street-cleaning tools and whereby the overhanging head of the said anchoring-member is similarly protected against displacement by street-cleaning tools.

My invention further consists in a concavo-convex sheet-metal traffic marker for pavements characterized as above and having certain other details of construction and combinations of parts as will be hereinafter described and particularly recited in the claims.

In the accompanying drawings:

Fig. 1 is a top or plan view of a marker as installed in the pavement;

Fig. 2 is a vertical central sectional view on the line 2—2 of Fig. 1, showing the plate-member of my improved marker pressed into the pavement and the drive-screw in position preparatory to its being driven through the central passage in the said plate;

Fig. 3 is a corresponding view, showing the drive-screw in place;

Fig. 4 is an edge view of the concavo-convex plate-member of my improved marker, detached;

Fig. 5 is an underside view thereof; and

Fig. 6 is an enlarged-scale sectional view on the line 6—6 of Fig. 5.

In carrying out my invention, as herein shown, I employ a concavo-convex sheet-metal plate or disk 10 having its central portion downwardly offsetting to form an annular recess 11 in its convex upper face and a supporting-shoulder 12 projecting from its concave under face. At equidistant points I

strike downward from the said shoulder four anchoring prongs 13 adapted to be embedded, as is also the rim 14 of the plate, in the surface of the pavement 15 so as to hold the said plate against lateral displacement. 60

For the purpose of preventing the upward displacement of the plate, as well as to supplement the prongs 13 and rim 14 in holding it against lateral displacement, I employ a drive-screw 16 having steep-pitch threads 17 65 and a relatively-large overhanging concavo-convex head 18 snugly fitting in the recess 11 of the plate in such manner as to cause its convex upper face to complement the curvature of the upper face of the plate 10. The 70 said drive-screw 16 passes downward into the pavement 15 through a central perforation 19 in the said plate, around which the metal is struck downward to form a conical socket 20 for the accommodation of the sloping shoulder 21 of the said drive-screw. 75

By providing the concavo-convex sheet-metal plate 10 with the supporting shoulder 12, the same is enabled to resist the pressure of traffic without deformation, so that its 80 superior visibility, due to its convex upper face is unimpaired. Furthermore, by virtue of the concave form of the under face of the plate, its rim 14 is enabled to embed itself in the pavement, so as not only to resist lateral 85 displacement but to prevent shovels, etc., of street-cleaners from accidentally prying it up. By seating the head 18 of the drive-screw 16 in the recess 11 of the plate, the rim of the same is also protected from being accidentally pried loose by street-cleaning tools. 90

I claim:

1. A traffic marker comprising a sheet-metal plate provided with a passage for the reception of an anchoring-member; one or more downwardly-projecting anchoring-prongs located adjacent the said passage; and an anchoring-member comprising a shank adapted to pass through the said passage into the pavement and a head adapted in size to overlie the said anchoring-prongs; whereby the said anchoring-prongs may be forced into the pavement concurrently with the shank of the said anchoring-member by force exerted 105 upon the latter.

2. A traffic marker comprising a sheet-metal plate struck downward to form a recess and provided with a passage intersecting the said recess; one or more downwardly- 110

projecting anchoring-prongs struck downward from the said recess adjacent the said passage; and an anchoring-member comprising a shank adapted to pass through the said passage into the pavement and a head adapted in size to overlie the said anchoring-prongs;

may be forced into the pavement concurrently with the shank of the said anchoring-member by force exerted upon the latter.

10

In testimony whereof, I have signed this specification.

EDWARD S. CORNELL, JR.
